POCKET CLIP

Russell T. Wing, Excelsior, Minn.

Application March 23, 1946, Serial No. 656,628

3 Claims. (Cl. 24—11)

1

This invention relates to pocket clips and has for its principal object to provide a device of that character which is well adapted for use with fountain pens and the like, and which operates in such a way as to grip the pocket with increasing force as any force tending to dislodge the pen is increased—except when the clip is intentionally released to facilitate withdrawal of the pen or pen receptacle.

Another object is to provide a pocket clip which is easy to attach to a pocket, and also easy to detach when it is the intention to do so.

All of the various embodiments of my invention have the common characteristic that the pocket-gripping portion of the clip is so mounted as to be movable, relatively to the pen barrel, only in a path so directed that any force applied to said pocket-gripping portion as a result of an effort to remove the pen from the pocket, without first releasing the clip, will increase the grip of said portion on the pocket frontpiece.

In each of the most practical applications of my invention, the pocket-gripping portion of the clip is arranged to be movable in an arcuate path, the center of which is so located that the pocket-gripping portion inherently moves along said arcuate path in a direction to increase its grip whenever, without having first released the clip, a force is applied tending to withdraw the pen or pen receptacle, as the case may be, from the pocket.

My invention is further characterized in that the pocket clip can easily be released, whenever it is the intent so to do; and the mechanism is of such character that attachment of the clip to a pocket can be accomplished more easily and quickly than is the case with pocket clips of the conventional type.

In the drawing which accompanies this specification:

Figure 1 is a front elevational view of a pen receptacle having a pocket clip in accordance with the invention;

Fig. 2 is a side elevational view of the same pen receptacle;

Fig. 3 is a fragmentary sectional view taken along line 3—3 of Fig. 2;

Fig. 4 is an internal view taken at line 4—4 of Fig. 1—the casing and pocket clip being shown in section in order to illustrate in full lines the

hair-pin spring which actuates the pocket clip and the manner of its securement;

Fig. 5 is a transverse sectional view taken along line 5—5 of Fig. 2; and

Fig. 6 is a transverse sectional view taken along line 6—6 of Fig. 2.

The drawing shows, on a greatly enlarged scale, an elongate, cup-like pen receptacle 1 designed to be carried in a vest or coat pocket, and a fountain pen 2 in the receptacle. The pen itself constitutes no part of the present invention.

A releasable locking means (not shown) of suitable construction may be provided.

Receptacle 1 is approximately rectangular externally in cross-section at its upper end, as shown in Figs. 5 and 6, but changes to a circular cross-section below.

Pressed into the open upper end of receptacle 1 and thus secured therein is a plug 3 which may be made of a suitable plastic material. Said plug has a circular bore 4 dimensioned to fit the pen barrel.

A U-shaped metal member 5 comprising a front plate 6 and two laterally-extending parallel arms 7 and 8 constitutes the principal element of a pocket clip. Arms 7 and 8 have inwardly turned ears 7a and 8a which are seated in apertures drilled through the wall of receptacle 1 and into the body of plug 3. Said ears function as pivots about which the member 5 is rotatable. The lower edge 6a of plate 6 functions as a jaw in cooperation with the adjacent front surface of receptacle 1 to secure the latter to a pocket frontpiece. When in use, the edge portion of a pocket frontpiece is situated in the space 9 (see Figs. 2 and 4).

As viewed in Figs. 2 and 4, clip 5 is continuously urged in a counterclockwise direction by means of a hair-pin shaped spring 10 which is disposed inside the receptacle. As shown most clearly in Fig. 5, the end 10a of spring 10 is bent right angularly to the leg of which it forms a part and is seated in a hole drilled in plug 3. The other end of spring 10 bears against an inwardly turned stud 7b forming an integral part of arm 7 and extending through a suitable slot in the adjacent wall of receptacle 1. Plug 3 is cut away along one side to provide clearance for spring 10 and stud 7b.

In Figs. 2 and 4, I have shown the member 5

in approximately the position it assumes when gripping a pocket frontpiece—making due allowance for the thickness of the gripped fabric. With the receptacle free from the pocket the jaw 6a presses against the adjacent front surface of the receptacle.

The end of jaw 6a moves in a path identified in Figs. 2 and 4 by the dot-dash arc 11; and the tangent to that arc at the tip of the jaw, at the position in which it is shown, is identified by dot-dash line 13. It will be apparent that at the limit of its travel, when gripping a pocket frontpiece, the jaw 6a is, to all intents and purposes, moving in a path defined by the tangent 13. Obviously, any force operating upwardly on receptacle 1 and tending to dislodge it from a pocket, while the clip is in gripping engagement with the frontpiece, will produce a downwardly directed counterforce on jaw 6a. This, manifestly, engenders a gripping force, normal to the vertical force couple, between jaw 6a and the adjacent surface of the receptacle. The greater the force tending to dislodge the receptacle, the greater will be the gripping force resisting dislodgment; and the smaller the angle A between the tangent line 13 and the line 14, which is parallel to the longitudinal axis of the receptacle, the greater will be the gripping force proportionately to the vertical force tending to dislodge the receptacle.

If maximum gripping force were the only factor to be considered, it clearly would be desirable to so design the clip as to obtain an angle A of very small magnitude. But, if the pivotal center of member 5 is so placed as to attain that end, the clip will not open to a satisfactory extent when an attempt is made to open it for attachment or release. Hence, as a practical matter, it is advisable to locate the pivotal center of member 5, not at the position which will produce the maximum gripping force but rather at a position which will produce a satisfactory gripping force while at the same time enabling the clip to open sufficiently so that it will not drag when the receptacle is being removed from the pocket and, further, so that it will not be difficult to attach the clip to the pocket frontpiece. There is no established optimum value for angle A but, in general, I have found that an angle of about thirty degrees gives good results. It is to be understood, however, that any angle within the range of angles between five degrees and seventy-five degrees may be employed without departing from the scope of my invention.

The clip is opened for both attachment and release by pressing on the upper edge portion of front plate 6.

There are various possible modifications within the ambit of my inventive concept and, accordingly, I do not wish to be limited except by the scope of the appended claims.

I claim:

1. In combination, an elongate receptacle open at its upper end and intended to be carried upright in a pocket and to be fastened thereto, a U-shaped clip member comprising a front plate and a pair of spaced parallel arms rigid therewith, said clip member being located near the upper end of said receptacle with said receptacle disposed between said arms, means pivotally connecting said arms to said receptacle for rocking movement about a fixed pivot so that the clip member is rotatable in a vertical plane, the lower edge of said front plate being operative as a jaw, in cooperation with the adjacent surface of said

receptacle, for gripping the frontpiece of a pocket, and a hair-pin spring situated inside said receptacle and anchored at one end, the other end of said spring being connected with one of said arms in such manner that it continuously urges said clip member, rotatively, in a direction such as to close the space between said jaw and the adjacent surface of the receptacle, the pivoted center of said clip member being located rearwardly of a longitudinal medial plane through said article whereby the lower edge of said front plate is movable along an arcuate path downwardly and toward said receptacle and upwardly and away from said receptacle, alternately, the tangent to said path at the point of contact of said lower edge with the pocket frontpiece extending at an angle of more than five degrees and less than seventy-five degrees to the longitudinal axis of said receptacle.

2. In combination, an elongate article adapted to be carried upright in the pocket, a rigid clip having a pair of arms at least partially embracing said article, and a jaw rigid with and extending from said arms downwardly along one side of said article with the free end thereof adapted to directly engage the side of said article, means pivotally mounting said arms on said article for rocking movement about a pivot fixed relatively to said article and said clip and located rearwardly of a medial longitudinal plane through said article and in a plane perpendicular to the longitudinal axis of the article and displaced upwardly from the free end of said jaw sufficiently whereby the tangent to the arc of movement of the free end of said jaw at the point of engagement between the free end of the jaw and the article makes an angle of between five degrees and seventy-five degrees with the side of the article, and spring means yieldingly urging the clip in a direction to cause the free end of the jaw to directly engage the side of said article.

3. In combination, an elongate receptacle, open at its upper end and intended to be carried upright in a pocket and to be fastened thereto, a plug inserted in the open end of said receptacle and secured therein, said plug having a bore extending lengthwise of the receptacle and adapted to accommodate a writing instrument, a U-shaped clip member comprising a front plate and a pair of spaced parallel arms, said clip member being located near the upper end of said receptacle, with said receptacle disposed between said arms and said front plate extending downwardly along said receptacle, means pivotally connecting said arms to said receptacle for rocking movement about a fixed horizontal axis so that the clip member is rotatable in a vertical plane, the lower edge of said front plate being operative as a jaw, in cooperation with the adjacent front surface of said receptacle, for gripping the frontpiece of a pocket, and a hair-pin spring situated inside said receptacle along one side thereof and anchored at one end to said plug and relatively free at the other end, one of said arms having a stud forwardly of said pivot axis and projecting into said receptacle into engagement with said other end of said spring whereby said spring urges said clip member, rotatively, in a direction such as to close the space between said jaw and the adjacent surface of the receptacle, the pivotal axis of said clip member being located rearwardly of a medial longitudinal plane through said article and upwardly from the lower edge of said front plate, whereby the lower edge of said front plate is movable along an arcuate

path downwardly and toward said receptacle and upwardly and away from said receptacle, alternately, the tangent to said path at the point of contact of said lower edge with the pocket front-piece extending at an angle of approximately thirty degrees to the longitudinal axis of said receptacle.
